CLAIM

The ornamental design for a casino handbag/carrying bag, as shown and described.

DESCRIPTION

FIG. 1 is a perspective view of the handbag;
FIG. 2 is a front elevational view of the handbag, the rear elevational view being a mirror image thereof;
FIG. 3 is a left side elevational view of the handbag, the right side elevational view being a mirror image thereof;

FIG. 4 is a top view of the handbag;
FIG. 5 is a bottom plan view of the handbag;
FIG. 6 is a top view of the handbag opened showing a middle pocket moved to left side;
FIG. 7 is a top view of the handbag opened showing the middle pocket moved to right side;
FIG. 8 is a top view of the handbag opened showing the middle pocket centered and partially open and showing hook and loop fasteners;
FIG. 9 is a front view thereof with the near side and the middle pocket of the handbag broken away to show the far side of the handbag interior; and,
FIG. 10 is a front view thereof with the near side of the handbag broken away to show the middle pocket within the handbag.

The broken line showing of paraphendia in FIG. 6 and 7 is for illustrative purposes only and forms no part of the claimed design.

FIG. 1FIG. 2*FIG. 3*FIG. 4*FIG. 5

FIG. 6FIG. 7*FIG. 8*FIG. 9*FIG. 10
